sham, Huntington Park, Calif.

Application August 7, 1935, Serial No. 35,105

7 Claims. (Cl. 166—14)

This invention relates to a device for use on a well and relates more particularly to a casing head for use on the upper end of a well casing. A general object of this invention is to provide 5 a practical, effective casing head that is very small and compact.

It is customary to provide a casing head on the upper end of the casing or casings of a deep well such as an oil well or gas well. The central 10 longitudinal opening of a casing head should be as large in diameter at its most restricted point as the opening in the casing to which it is applied. Because of this requirement it has been the usual practice to make casing heads of great 15 length or vertical height to accommodate the slips, packers, etc., for suspending and sealing about the inner casing or casings. Thus the casing heads that have been in general use are large, bulky and heavy and are usually costly because 20 of their size.

Another object of this invention is to provide a casing head that is small, compact and light in weight, and that embodies a minimum number of simple, inexpensive parts.

25 Another object of the invention is to provide a casing head for arrangement on the upper end of an outer casing and that is of minimum height or vertical dimension and that is operable to carry or suspend an inner casing considerably 30 smaller in diameter than the outer casing.

Another object of this invention is to provide a casing head of the character mentioned that embodies a simple, effective means for carrying or suspending an inner casing that does not necessitate the lengthening of the body and that 35 is operable to suspend an inner casing much smaller in diameter than the outer casing.

A further object of this invention is to provide 40 a casing head of the character mentioned embodying a novel and particularly effective means for sealing or packing off between the inner casing and the body to prevent the loss or leakage of pressure and fluid.

Another object of the invention is to provide 45 a head for a well that is operable to dependably land and seal between an outer well casing and an inner casing.

Another object of the invention is to provide 50 a compact, and inexpensive landing head for landing an outer casing and an inner casing.

The various objects and features of our invention 55 will be fully understood from the following detailed description of typical preferred forms and application of the invention, throughout

which description reference is made to the accompanying drawings, in which:

Fig. 1 is a central longitudinal detailed sectional view of one form of casing head provided by this invention showing it in position on the upper end of an outer casing and illustrating an inner casing suspended by the head. Fig. 2 is a reduced horizontal detailed sectional view taken substantially as indicated by line 2—2 on Fig. 1. Fig. 3 is a fragmentary vertical detailed 10 sectional view taken substantially as indicated by line 3—3 on Fig. 1. Fig. 4 is a vertical sectional view of the base of another form of the invention landing or suspending an outer casing. Fig. 5 is a view similar to Fig. 4 showing the head 15 fully assembled and suspending and sealing about an inner casing, and Fig. 6 is a view taken as indicated by line 6—6 on Fig. 5.

The form of the invention illustrated in Figs. 1 to 3, inclusive, includes, generally, a body 10 adapted to be connected to the upper end of an outer well casing C, means 11 in the body 10 for supporting or suspending an inner casing A, a flange section or upper section 12 on the body 10, and means 13 for sealing or packing between the 25 body 10 and the inner casing A.

The body 10 is an annular or tubular member adapted to be attached to or applied to the upper end of the outer well casing C. In accordance with the broader aspects of the invention 30 the body 10 may be mounted on or attached to the casing C in any practical manner. In the particular case illustrated in the drawings the lower portion 14 of the longitudinal body opening 15 is enlarged in diameter and is screw threaded 35 to receive the threaded upper end portion of the casing C whereby the body may be threaded on the casing as shown in the drawings. In accordance with the invention the body 10 is comparatively short and projects a relatively short distance above the upper end of the casing C. An outwardly projecting annular flange 16 is provided on the upper end of the body 10 to receive or connect with the upper section 12 as will be hereinafter described. The upper portion 17 of 40 45 the body opening 15 is of enlarged diameter forming or providing a seat 18 on the interior of the body 10. The seat 18 is preferably inclined downwardly and inwardly as illustrated in Fig. 1 of the drawings. Gas outlets or ports 19 are 50 provided in the upper wall of the body 10. It is a feature of the invention that the ports 19 are cored or formed through the upper wall portion of the body and the flange 16 as clearly shown in Figs. 1 and 2 of the drawings, so that 55

the ports 19 do not necessitate elongation of the body. Recesses 9 are provided in the interior of the body and extend through the seat 18 to put the ports 19 in communication with the interior 5 of the casing C. Internally threaded bosses 20 may be provided at the ports 19 to receive the threaded ends of conduits or pipes 21 for carrying the gas or fluid from the ports.

The means 11 which is operable to dependably 10 carry or suspend the inner casing A is such that its arrangement or provision in the body 10 does not necessitate lengthening of the body. The casing suspending means 11 includes a tubular liner or spider 22 seated in the tubular body 10. 15 The exterior of the upper portion of the spider 22 conforms to and fits in the enlarged upper portion 17 of the body opening 15 and the spider is provided with a downwardly and inwardly inclined shoulder 23 which rests on or cooperates 20 with the seat 18. The cooperation of the shoulder 23 with the seat 18 of course supports the spider 22 in the body opening 15. The upper end of the spider 22 is preferably substantially flush with the upper end of the body 10. The spider 22 extends downwardly through the body opening 15 and projects into the upper end portion of the outer casing C. It is this extension or projection of the spider 22 into the casing C that permits the body 10 to be of minimum vertical dimension as will be readily understood. The exterior of the lower portion of the spider 22 may be downwardly and inwardly tapered to pass through the opening 15 and enter the casing C with suitable clearance. The lower end of the spider 22 may be in substantially the same horizontal plane as the lower end of the body 10. The spider 22 formed and mounted as just described may be of the same length or vertical dimension as the body 10 without projecting beyond the upper or lower limits of the body. The internal surface or wall 24 of the spider 22 is tapered or inclined downwardly and inwardly.

The means 11 for suspending the casing A includes slips 25 adapted to be seated in the spider 45 22 and operable to grip the inner casing A. The slips 25 have transversely curved and downwardly and inwardly inclined external surfaces 29 for cooperating with the inclined internal surface 24 of the spider 22. The inner sides of the slips 25 are cylindrically concaved and provided with teeth 26 facing upwardly and inwardly to grip the inner casing A. It will be noted that the spider 22 may be as long as the body 10 or may be longer than the body 10 if desired 50 and, therefore, has a long internal seat or surface 24 for carrying the slips 25. Accordingly, the slips 25 may be sufficiently long to effectively and dependably support the inner casing A without requiring that the body 10 be of any greater 55 length than illustrated in the drawings. In practice the upper ends of the slips 25 may be spaced some distance below the upper end of the spider 22 when the slips are in active supporting engagement with the inner casing A. Threaded 60 sockets 27 may be provided in the upper ends of the slips 25 to receive threaded parts of lifting tools. The adjacent longitudinal edges or sides of the slips 25 may have overlapping parts 28.

70 The flange section or upper section 12 of the head is arranged at the upper end of the body 10 to facilitate the connection of a tubing head, a nipple, a Christmas tree fitting or the like, to the casing head. The section 12 may be a simple integral member whose lower portion con-

stitutes an annular flange 30 which opposes and is complementary to the flange 16 of the body. Bolts 31 extend through aligned openings 32 in the flanges 16 and 30 and nuts 33 are threaded on the bolts to connect the section 12 with the body 10. The upper portion 34 of the section 12 is tubular having a vertical opening 35 which is at least as large in diameter as the opening of the inner casing A. In the preferred form of the invention the upper portion 34 of the section 12 is both internally and externally threaded to facilitate the connection of a tubing head, nipple, pipe or the like, with the section 12. In the particular case illustrated in the drawings we have shown a nipple 36 threaded in the portion 15 34 of the flange section 12. The nipple 36 may be considered as extending to a tubing head or a Christmas tree.

The means 13 for sealing and packing about the inner casing A is simple and particularly effective and dependably seals off between the inner casing A and the body 10, thus sealing off between the inner and outer casings A and C. The means 13 includes a plate or ring 37 adapted to surround the upper end portion of the inner casing A. In practice the inner casing A is cut to extend some distance into the upper section 12 and the ring 37 surrounds the casing A within the section 12. The ring 37 extends outwardly across the upper ends of the slips 25 and the spider 22. An annular groove 38 is provided in the upper side of the ring 37 at or in communication with the vertical opening 39 of the ring. A gasket or body 40 of packing such as lead or the like is arranged in the groove 38. An annular rib or flange 41 projects from the lower side of the section 12 and extends into the groove 38 to bear on the body of packing 40.

The means 13 includes or provides opposing or registering annular grooves in the upper internal corner of the body 10 and the upper outer corner of the spider 22 which, together, form a groove 42 for carrying a gasket or body of packing 43. An annular rib or flange 44 projects downwardly from the ring 37 and extends into the groove 42 to bear on and compress the body of packing 43. When the parts are assembled as shown and the nuts 33 are tightened, the flange 41 bears downwardly on the body of packing 40 and urges or forces the ring 37 downwardly so that its flange 44 is in turn pressed or forced against the body of packing 43. Thus the pressures on the bodies of packing 40 and 43 are equalized. It will be clear that the body of packing 40 forms a tight effective seal between the inner casing A and the ring 37 and between the inner casing A and the section 12. In a like manner the body of packing 43 provides a tight effective seal between the ring 37, the body 10 and the spider 22. Threaded sockets 45 may be provided in the upper side of the ring 37 to receive a lifting tool or tools to facilitate the handling of the ring. From the above it will be seen that the means 13 fully and effectively seals off the upper end of the annular space between the outer string or casing C and the inner string or casing A.

Assuming that the outer casing C has been run into the well bore and cemented in the usual manner, its upper section is cut at the desired point and is threaded for the reception of the body 10. The body 10 may be readily threaded to the upper end of the casing C to be in the position illustrated in the drawings. The drilling of the well is then continued until the well 75

is of the desired depth whereupon the inner string of casing A is run into the well and cemented. An auxiliary spider or other means (not shown) may be employed to run the inner casing A into the well. After the cement sealing about the lower end of the inner casing A has set the inner casing is cut off a suitable distance above the upper end of the body 10. The spider 22 is then arranged in the body opening 15 so that its shoulder 23 bears on the seat 18. The inner casing is then put under a suitable tensile strain and the slips 25 are inserted in the spider 22 to grip the inner casing A and maintain the tensile strain on the casing. The body of packing 43 is then arranged in the groove 42 and the ring 37 carrying its body of packing 40 is then positioned so that its flange 44 bears on the body of packing 43. Following the positioning of the ring 37, the upper section 12 is arranged in place and bolted to the body 10. As described above, the tightening of the nuts 33 causes the flange 41 to be forced downwardly against the body of packing 40 so that a downward force is transmitted to the ring 37. The flange 41 bearing downwardly against the body of packing 40 insures an effective seal between the inner casing A and the ring 37 and between the inner casing A and the upper section 12. The body of packing 43 tightly seals off between the ring 37 and the body 10 and the spider 22. Thus an effective seal is provided about the inner casing A to prevent the leakage and loss of fluid and pressure. Following the installation of the casing head the nipple 36 or a similar part, or a tubing head may be connected with the upper portion 34 of the section 12 as conditions may require.

The casing head shown in Figs. 1, 2, and 3 is effective and dependable in supporting and sealing about an inner well casing. Due to the formation and arrangement of the spider 22 and the slips 25 which extend into the outer casing A, the body 10 may be of a minimum vertical dimension. The body 10 may be made comparatively short without requiring that the spider 22 or the slips 25 be shortened. The ring 37 being arranged within the upper section 12 does not necessitate the lengthening of the body 10. Accordingly, the casing head of the present invention is small and compact and light in weight. The various parts of the head are simple and inexpensive of manufacture and are easy to handle and install.

The form of the invention illustrated in Figs. 4, 5, and 6 of the drawings includes, generally, a base 50 adapted to be connected with an outer casing O, a body 51 for arrangement on the base 50, means 11 in the body 51 for suspending the inner casing I, an upper section 12, and means 13 for sealing between the body 51 and the inner casing I.

The head or device shown in Figs. 4, 5, and 6, is operable to land or secure the outer casing O and suspend the inner casing I and, therefore, may be termed a landing head. The base 50 of the head is provided to land or secure the upper end of the outer casing O. The base 50 constitutes the lower part or section of the head and has a comparatively large horizontal flange 52 adapted to seat on a suitable support. In practice the flange 50 may rest on the floor F of the cellar of the well derrick. The base 50 extends upwardly from its flange 52 and has a central longitudinal opening 53 for rather closely receiving the outer casing O. An outwardly projecting radial flange 54 is provided at the upper

end of the base 50. After the outer casing O has been run into the well and cemented in the usual manner it is cut off at its upper end and the base 50 is arranged on the support or floor F and is welded to the outer casing O as at 55 so that a seal is provided around the upper end of the casing and so that the base supports or secures the casing from its upper end.

The invention provides a nipple or fitting 56 for facilitating the connection of a blowout preventer with the base 50 when the well is being deepened to receive the inner casing I. The fitting 56 has a flange 57 at its lower end adapted to oppose the flange 54. The flange 54 has an annular groove 58 in its upper end for carrying packing 59. An annular flange or tongue 60 on the lower face of the flange 57 is adapted to enter the groove 58 and bear on the packing 59. Studs or bolts 61 are arranged through openings 62 in the flanges 54 and 57 to connect the fitting 56 with the base 50 and to compress the packing 59. The fitting 56 may be internally or externally threaded to receive a pipe or part 63 of a blowout preventer.

The body 51 is provided to carry the means 11 for suspending the inner casing I. When the well has been drilled or deepened to receive the inner casing I the inner casing is run into the well and cemented in the usual manner. The fitting 56 is removed from the base 50 and the body 51 is positioned on the upper end of the base 50. It is to be understood that it may be necessary to cut the inner casing I at a suitable point above the upper end of the base 50 after the inner casing has been cemented in the well. The body 51 is a tubular member having a central longitudinal opening 64. The body opening 64 receives or passes the inner casing I with considerable clearance and has an upwardly facing inclined shoulder 66. A rib or tongue 67 is provided on the lower face of the lower body flange 65 and is adapted to enter the groove 58 to compress the packing 59. Fluid ports 68 are provided in the wall of the body 51. In the particular case illustrated in the drawings the ports 68 are threaded to receive the end portions of the conduits or pipes 69 for conducting the fluid. Recesses 70 are provided in the interior of the body 51 and extend downwardly from the ports 68 past the shoulder 66 to maintain the pipes 69 in communication with the interior of the outer casing O as will be hereinafter described.

The means 11 for suspending the inner casing I, the upper section 12 and the packing means 13 may be identical with the means 11, the section 12 and the packing means 13 of the previously described form of the invention and corresponding reference numerals have been employed in Figs. 5 and 6 to indicate their respective parts and elements. The means 11, the section 12 and the packing means 13 being identical with the same elements of the previously described form of the invention it is believed unnecessary to specifically describe them at this point and reference is hereby made to the foregoing detailed description of these elements. It is to be noted, however, that the flange 30 of the section 12 is of the same diameter as the flange 54 and that bolts 75 extend through the openings 32 in the flange 30, and the openings 62 in the base flange 54. The flange 44 cooperates with the groove 42 and the tongue 67 cooperates with the groove 58 to properly centralize and align the several parts of the assembly. With this construction the tightening of the nuts 18 75

on the studs or bolts 75 actuates or compresses the packing 40, the packing 43 and the packing 59 and holds the several parts of the head in their proper assembled relation. It will be noted that the spider 22 projects downwardly into the outer casing O with substantial clearance so that there is free communication between the pipes 69 and the interior of the casing O through the medium of the recesses 70.

10 After the outer casing O has been run into the well and cemented in the usual manner the base 50 may be welded to its upper end as described above to form a support or securing means for the upper end of the outer casing. The drilling 15 of the well may then be continued until the well is of the desired depth whereupon the inner string of casing I is run into the well and cemented. During the deepening of the well or drilling of the well through the casing O it may be necessary or desirable to provide a blowout 20 preventer at the upper end of the well to control the well in the event that high pressures are encountered. A blowout preventer of any desirable type may be readily secured to the base 50 by means of the fitting 56 and the pipe or part 25 63 or the like. It is to be understood that the fitting 56 is disconnected or removed from the base 50 when the inner casing I is run into the well and set. An auxiliary spider or other means 30 may be employed to run the casing I into the well. The inner casing I is cut off to project a suitable distance above the body 51.

The body 51 may be readily positioned on the base 50 so that its tongue 67 bears on the packing 35 59. The spider 22 is then arranged in the body so that its shoulder 23 rests on the seat or shoulder 66. The slips 25 are then inserted in the spider to grip the inner casing I and maintain the tension on the inner casing. The packing 43 40 is positioned and the ring 37 arranged about the upper end part of the inner casing I so that its tongue or flange 44 bears on the packing 43. The ring 37 may carry the packing 40 and the upper section 12 is arranged in position so that its 45 tongue or flange 41 bears on the packing 40. The studs or bolts 75 are then inserted and the nuts 76 tightened down so that the body 51 is properly secured to the base 50 and the upper section 12 is properly secured to the body. Tightening 50 of the nuts 76 also compresses and actuates the packing 40, 43, and 59. The means 13 effectively seals about the inner casing I and packs off between the inner casing I and the body 51 thus sealing off the upper end of the annular space 55 between the inner and outer casings. The means 11 dependably suspends the inner casing I from its upper end and may maintain the inner casing under a desirable tension. The recesses 70 connecting the pipes 69 with the upper end of the outer casing O maintain the communication between the outer casing O and the pipes. It is to be noted that the landing head illustrated in Figs. 4, 5, and 6 of the drawings is very simple and compact and dependably and effectively lands 60 65 or secures the upper end of the outer casing O and suspends the inner casing I.

Having described only typical preferred forms and applications of our invention, we do not wish to be limited or restricted to the specific details 70 herein set forth but wish to reserve to ourselves any modifications or variations that may appear to those skilled in the art or may fall within the scope of the following claims:

Having described our invention, we claim:

75 1. A casing head including a body adapted to

be connected with the casing of a well, the body having an opening in vertical alignment with the opening in the casing, a seat in the body, a spider arranged in the body and resting on said seat, there being a fluid port in the wall of the body 5 above the seat, and slips in the spider for suspending an inner casing.

2. A casing head including a body adapted to be applied to the casing of a well, the body having an opening registering with and forming a 10 continuation of the opening in the casing, a spider arranged in the body opening, slips in the spider for carrying an inner casing, an upper section secured to the body, packing carried by the body, a member surrounding the inner casing and 15 bearing on the packing, and packing on the member sealing about the inner casing engaged and held under pressure by the upper section whereby the first mentioned packing is held under pressure by the member. 20

3. A casing head including a body adapted to be applied to the casing of a well, the body having an opening registering with and forming a continuation of the opening in the casing, a spider arranged in the body opening, slips in the 25 spider for carrying an inner casing, an upper section secured to the body, an upwardly facing shoulder in the body, packing for sealing with the shoulder, a member surrounding the inner casing and bearing on said packing, packing on the 30 upper side of the member operable to seal about the inner casing and seal with the member, and a part on the upper section bearing downwardly on the second mentioned packing.

4. A casing head including a body adapted to 35 be applied to the casing of a well, the body having an opening registering with and forming a continuation of the opening in the casing, a spider arranged in the body opening, slips in the spider for carrying an inner casing, an upper section secured to the body, an upwardly facing shoulder 40 on the body, an adjacent upwardly facing shoulder on the spider, a packing ring seated on and adapted to seal with the shoulders, a member surrounding the inner casing above the spider, 45 a body of packing adapted to seal between the member and inner casing, a part on the upper section bearing downwardly on the body of packing to actuate the same, the body of packing transmitting the downward pressure to the member, and a part on the member bearing downwardly on said packing ring to actuate the same. 50

5. A casing head including a body adapted to be applied to the casing of a well, the body having an opening registering with and forming a 55 continuation of the opening in the casing, a spider arranged in the body opening, slips in the spider for carrying an inner casing, an upper section secured to the body, an upwardly facing shoulder in the body, packing for sealing with 60 the shoulder, a member in the upper section surrounding the inner casing and bearing on said packing, packing on the upper side of the member operable to seal about the inner casing and seal with the member, and a part on the upper 65 section bearing downwardly on the second mentioned packing.

6. A casing head including a body adapted to be applied to the casing of a well, the body having an opening registering with and forming a 70 continuation of the opening in the casing, a spider arranged in the body, slips in the spider for carrying an inner casing, an upper section on the upper end of the body, a flange and bolt connection between the body and upper section, 75

and means for sealing between the body and the inner casing actuated by tightening the flange and bolt connection, said means including packing for sealing with the body, a member bearing on the packing, packing for sealing with the inner casing and the member, and a part on the upper section bearing on the last named packing to actuate both the packings.

5 7. A head for a well including a body adapted to be connected with the upper end of a well casing and having a vertical opening in communica-

tion with the casing, an upwardly facing shoulder on the interior of the body, the body having a fluid port in its wall above the shoulder and an internal recess extending downwardly through the shoulder, a spider seated on the shoulder and projecting downwardly into said casing with clearance whereby said casing communicates with the port through the recess, and slips in the spider for carrying an inner casing.

5

HARRY P. WICKERSHAM. 10
ERWIN BURNS.
